Des. 194,080
Patented Nov. 13, 1962

194,080

ELECTROSTATIC PHOTOCOPY APPARATUS

Thomas E. Hanson, Syracuse, and Chester J. Abend,
Camillus, N.Y., assignors to Smith-Corona, Marchant,
Inc., Syracuse, N.Y., a corporation of New York

Filed Dec. 5, 1961, Ser. No. 67,806

Term of patent 14 years

(Cl. D61—1)

FIG. 3

FIG. 3

FIG. 4

FIGURE 1 is a perspective view of an electrostatic photocopy apparatus showing our new design;

FIGURE 2 is a front elevational view thereof;

FIGURE 3 is a left-hand elevational view thereof, on a reduced scale;

FIGURE 4 is a top plan view thereof; and

FIGURE 5 is a rear elevational view thereof.

The dominant features of our design are shown in full lines.

We claim:

The ornamental design for electrostatic photocopy apparatus, substantially as shown and described.
